Primary Examiner — David Muller

CLAIM

An ornamental design for a handle design for catheter Y-hub with dual side ports, as shown and described.

DESCRIPTION

FIG. 1 is a three-quarter front isometric view of a handle design for catheter Y-hub with dual side ports.

FIG. 2 is a three-quarter rear isometric view of the handle design for catheter Y-hub with dual side ports shown in FIG. 1.

FIG. 3 is a top plan view thereof;

FIG. 4 is a bottom plan view thereof;

FIG. 5 is a left side elevation view thereof;

FIG. 6 is a right side elevation view thereof;

FIG. 7 is a rear elevation view thereof; and,

FIG. 8 is a front elevation view thereof.

The broken line showing of parts of the drawings is included for the purpose of illustrating use and environment and forms no part of the claimed design.

1 Claim, 5 Drawing Sheets
